UNITED STATES PATENT OFFICE.

JOHN H. DIXON, OF PITTSBURG, PENNSYLVANIA.

AUTOMATIC SPRINKLER.

No. 838,963.

Specification of Letters Patent.

Patented Dec. 18, 1906.

Application filed December 2, 1901. Serial No. 84,451.

To all whom it may concern:

Be it known that I, JOHN H. DIXON, of the city of Pittsburgh, county of Allegheny, and State of Pennsylvania, have invented a new and useful Improvement in Automatic Sprinklers, of which the following is a full, clear, and exact description, reference being had to the accompanying drawings, forming part of this specification, in which—

Figure 1 is a side elevation, partly broken away, of a sprinkler system embodying my invention. Fig. 2 is a diagrammatic view of the distributing system. Fig. 3 is a top plan view of the sprinkler-head. Fig. 4 is a side view, partly in section, of the head and attachments with one of the valves opened. Fig. 5 is a detail view showing the cord attachment which I prefer to employ and the locking devices in connection therewith. Figs. 6, 7, 8, and 9 are further views showing the cord arrangement. Fig. 10 is a side elevation of the tank-valve, and Fig. 11 is a diagrammatic plan view showing another coupling system.

My invention relates to the class of sprinklers commonly used for the purpose of extinguishing fires in buildings and is applicable to the two systems known, respectively, as the "wet" and "dry" systems, the former being a system in which the water is carried in the distributing-pipe at all times and the latter a system in which the water is held back by air-pressure against an inlet-valve until such time as the pressure has been released.

The object of my invention is to provide a novel form of sprinkler having one or more outlet-openings, together with a valve or valves controlling the openings, and a fusible link arranged to open the valve or valves when melted.

My invention also provides a sprinkler-head which is not affected by heat acting directly upon the heads and which may be used in connection with pipes which also serve as the pipes of a steam-heating system.

It also provides a head which is applicable to the use of steam as an extinguishing medium and which is free from fusible joints, which would be likely to be strained by water-hammering or other internal dynamic action.

With these objects in view my invention consists in the novel construction, arrange-

ment, and combination of parts, all substantially as hereinafter described, and pointed out in the appended claims.

In the accompanying drawings, the numeral 1 represents a supply-tank; 2, a stand-pipe leading therefrom and having a plurality of branch pipes 2'.

3 is a by-pass pipe tapped into the pipe 2 below the bottom of the tank and extending over and within the latter.

4 indicates a steam connection; 5, a pump connection.

6 represents fire-engine couplings of a branch pipe 7, which is provided with check-valves 7', the pipe 7 being designed to extend to the exterior of the building.

The upper end of the pipe 2 is closed by a valve 14, to which is connected a cord 13, having a weight 13 at its lower end which is normally prevented from opening the valve by means of a latch device 12 12'. The latch member 12 is controlled by a weight 10 on an extension-cord 11, having branches 9 extending through the different parts of the building, the arrangement being such that any slack in the cords 9 will cause the weight 10 to release the latch 12 12', thereby freeing the weight 13 and opening the valve 14.

My improved sprinkler-head, as shown in Figs. 3 and 4, is provided with two or more outlet-openings pointing in different directions and closed by means of valves 21. Connected to each valve is an arm 21', which normally supports the valve in closed position by means of its engagement with a hinged brace 22, which engages the arm 21' and also the portion 18' of the head. This hinged brace is supported by a link or hanger 25, which is secured at its upper end in the short arm 16' of a lever 16, pivoted to the arm 17 of the head. Each lever 16 is normally held in the position shown at the right-hand side of Fig. 3 by means of a fusible link 15. 18' represents deflectors, which are arranged opposite the respective outlet-openings of the head.

Resting on the portion 18' of the head and normally held by pins 20 on the short arms of the lever 16 is a triangular catch 19, to which a cord 9 is connected. These cords, as shown in Figs. 7 and 8, may extend over eyes or pulleys 24', carried by clamps 24, screwed to the branch pipes of the distributing system.

The operation is as follows: When any one of the fusible links 15 is subjected to an abnormal temperature, it fuses and causes the lever 16 to tilt into the position shown at the 5 left-hand side of Fig. 3. This releases the jointed brace 22, and thereby the valve 21. The movement of the lever 16 also releases the catch 19, as shown in Fig. 9, which permits the weight 10 to release the latch 12 12', 10 and thereby cause the valve 14 to open. The extinguishing fluid enters the distributing system and unseats the valve 21, which drops to the floor.

The above is descriptive of the operation 15 of the "dry" system. Where the "wet" system is employed, it is only necessary to maintain the valve 14 in an open position. This valve 14 is set in a cage 14', as shown in Fig. 10, and is designed to work freely in said 20 cage against the valve-seat 14' while water is being pumped into the tank through the stand-pipe 2. This valve is not supposed to act when steam is admitted into the pipes for heating or extinguishing purposes, in 25 such cases the by-pass 3 being used. The check-valve 3' in this pipe prevents the water siphoning back into the system from any cause.

In the arrangement shown in Fig. 11 a 30 quadruple valve-head is employed, there being four outlet-openings at ninety degrees apart. The valves for these openings may be operated by a similar arrangement to that shown in Figs. 3 and 4 for the double head, 35 a lever 16 with its adjuncts being employed for each valve.

Various changes may be made in the details of the parts without departing from my invention, since

What I claim is—

1. In an automatic sprinkler system, a sprinkler-head having a series of outlet-openings pointing in different directions, valves controlling said openings, and a fusible link arranged to open at least one of said valves 45 when melted; substantially as described.

2. In an automatic sprinkler system, a single sprinkler-head having a plurality of discharge-outlets, valves controlling said outlets, and a series of fusible links, one connected to each valve of the head and arranged to open it when fused; substantially as described.

3. In automatic sprinkler systems, a head having a side exit, a fusible link at one side 55 of the supply-pipe and laterally separated from the head, a valve for the opening controlled by the link, and a deflector between the valve and the link; substantially as described.

4. In automatic sprinkler systems, a sprinkler-head having a plurality of discharge-openings pointing laterally in different directions, a series of fusible links, one beyond and in the direction of each opening, 65 and connections between each fusible link arranged to open the valve when the link is fused; substantially as described.

JOHN H. DIXON.
